UNITED STATES PATENT OFFICE.

JOHN W. THOMAS, OF ALLENTOWN, PENNSYLVANIA.

DESIGN FOR A CLUSTER-ELECTROLIER.

No. 39,286.

Specification for Design.

Patented April 28, 1908.

Application filed March 25, 1908. Serial No. 423,283. Term of patent 14 years.

To all whom it may concern:

Be it known that I, JOHN W. THOMAS, a citizen of the United States, residing at Allentown, in the county of Lehigh and State of Pennsylvania, have invented a new, original, and ornamental Design for Cluster-Electroliers, of which the following is a specification, reference being had to the accompanying drawing, forming part thereof.

The figure is a perspective view of a cluster electrolier, showing my new design.

I claim:

The ornamental design for a cluster electrolier, as shown.

JOHN W. THOMAS.
